H. J. Meader.

UNITED STATES PATENT OFFICE

1,966,373

GARMENT HANGER

Charles T. Balochi, Roanoke, Va.

Application March 15, 1933, Serial No. 660,950

1 Claim. (Cl. 223—64)

This invention relates to garment hangers and its general object is to provide a garment hanger that renders garments insect and moth proof, in that it is constructed to receive moth or other insect exterminating or preventing material, such as gas producing chemicals, moth balls or the like, the fumes, odors, and vapors of which impregnate the garment but the material does not contact the same and casual removal of the material is prevented.

Another object of the invention is to provide a garment hanger of the character set forth, that can be associated with any type garment without injury thereto, is inexpensive to manufacture, simple in construction, easy to load and unload and is extremely efficient in use and service.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a view of a garment hanger constructed in accordance with the present invention, with parts in section and elevation.

Figure 2 is a sectional view taken approximately on line 2—2 of Figure 1, looking in the direction of the arrows.

Figure 3 is a sectional view taken approximately on line 3—3 of Figure 1, looking in the direction of the arrows.

Referring to the drawing in detail, it will be noted that the garment hanger in the form as shown includes a body having a central enlarged portion 1 from which extends in diverging relation therefrom and upon opposite sides thereof arms 2 and 3 which are preferably provided with curved upper surfaces 4 that merge into the enlarged portion 1, the latter having a circular upper surface and secured therein and rising therefrom is a suspending hook 5.

The arms 2 and 3 have arranged in the confronting faces thereof adjacent the lower ends bores to receive the opposite ends of a brace bar 6 that bridges the arms as clearly shown in Figure 1.

Each of the arms are hollow for a portion of their length to provide chambers 7 which have their inner ends extending into the central enlarged portion 1 and disposed in communication with each other, while their remote ends terminate adjacent to the outer ends of the arms. The chambers are provided with an inlet means at the point of communication with each other, and this inlet means is provided with suitable closing

means such as a stopper 8, which in the form as shown is frictionally held in the bore that constitutes the inlet means as clearly shown in Figure 1.

The chambers are preferably round in cross section and extending longitudinally of the arms and preferably in the sides and under portion thereof is a plurality of slots 9 that are disposed in communication with the chambers as best shown in Figure 3.

It will be noted that I have shown moth balls or the like arranged in the chambers 7, but any gas producing chemicals in lump form, and in any shape and size that is capable of being disposed in the chambers may be arranged therein, and of course the balls and chemicals are disposed through the inlet means and retained in the chambers by the stopper 8.

From the above description and disclosure of the drawing, it will be obvious that I have provided a garment hanger capable of receiving insect exterminating and preventing material, to render garments hung thereon insect and moth proof, as the fumes, odors and vapors from the material will escape through the slots 9 and impregnate the garment, and I want it understood that the hanger can be made from any material, but it is preferred that wood be used for the body, arms and the brace bar. However, the latter can be made from metal.

It is thought from the forgoing description that the advantages and novel features of my invention will be readily apparent.

I desire it to be understood that I may make changes in the construction and in the combination and arrangement of the several parts, provided that such changes fall within the scope of the appended claim.

What I claim is:

A garment hanger comprising a body including an enlarged portion, arms formed with and extending in diverging relation from the enlarged portion, said arms having communicating chambers arranged longitudinally therein to receive insect exterminating and preventing material, inlet means for said chambers at the juncture thereof to allow the material to gravitate therein, closure means for the inlet means, said arms having slots communicating with the chamber and the atmosphere, and suspending means for said hanger and secured to and rising from said enlarged portion.

CHARLES T. BALOCHI.
